UNITED STATES PATENT OFFICE.

JOHN TAYLOR BOYD, OF VALDOSTA, GEORGIA.

PLANT PROTECTOR.

Application filed July 23, 1926. Serial No. 124,500.

This invention relates to plant protectors of that type embodying a support and a cover separably held thereby for the purpose of placement over young plants, to protect 5 the same from extreme cold or heat and at the same time provide sufficient ventilation.

The improved protector solely comprises two parts, namely, the support and the covering device, which may be readily applied 10 to and removed from the support, and may be manufactured at a comparatively small cost.

In applying the improved protector over plants, the support is reliably held in the 15 position desired by embedding a portion thereof within the ground, and to stabilize the support, an opposite member thereof serves to prevent the same from being overturned or loosened from its applied position. 20 Prior to the application of the support relatively to the plant to be protected, the cover member or device is easily associated with and positively held by the support, for practical application of the complete device over 25 a plant.

The invention also consists in the preferred construction and arrangement of the several parts of the plant protector which will be more fully hereinafter described and 30 claimed.

In the drawing:

Fig. 1 is a perspective view of the improved plant protector shown in protecting position relatively to a plant.

Fig. 2 is a transverse vertical section 35 through the protector shown in applied position.

Fig. 3 is a detail perspective view of the support.

As hereinbefore noted, the improved protector comprises a support, generally designated by the reference character 5, and a cover or shield 6. The support is arched and is formed of wire of suitable gage and preferably of a non-corrosive character, the wire being twisted at an intermediate point, as at 7, to give the same body strength and also to facilitate application or placement and withdrawal of the support relatively to the ground. The intermediate twisted body portion 7 will be preferably located at the top of the protector when the support is completed. From this intermediate twisted body portion 7 the wire, which has been doubled, is continued downwardly at an angle at one side by long twists 8, to pro-

vide a supporting leg 9 terminating at its lower end in a prop loop 10, which is adapted to engage the top surface of the ground. From the intermediate arched and twisted 60 body portion 7 the opposite side of the support comprises divergent legs 11 and 12 of similar construction and longer than the leg 9, so that the lower free extremities 13 of the legs 11 and 12 may pierce to be embedded in the ground. The upper portions of the legs 11 and 12 are rebent, thus forming a substantially flattened S-shaped double loop on each leg to provide elongated 65 slots 14. The parts of this rebent formation are parallel, or the wire in its rebent shape is preserved in straight condition and the openings to the slots 14 are at the top, the lower terminal bends 15 of these slots having an equal dependence relatively to 70 the upper openings of the slots and serve to limit the insertion in the slots of a portion of the cover or shield. The slots 14 are of considerable length so as to positively engage and hold the portion of the cover or 75 protector 6 which is fitted thereto.

The cover or shield 6 as shown is preferably in the form of a fruit basket of suitable dimensions having a rectangular contour, said fruit basket, as will be understood, being formed from veneer strips and provided with an edge binding. In this type of basket the sides and ends flare outwardly from the bottom and thereby very efficiently serve as a cover or shield means for placement 90 over plants when applied to the support 5, as hereinbefore explained. It will be understood, however, that other cover or shield means may be adopted, but the basket type has been found in practice to be durable and 95 readily obtainable at a small cost and is exceptionally practicable in performing its function as a cover or shield.

The improved plant protector is prepared for service by first inserting one side of the cover or shield 6 in the slots 14 and the legs 9 and 11 and 12 will be in such spaced relation that the leg 9 will lie close to the side of the cover or shield 6 opposite that fitted in the slots 14. After the support and cover or shield have been assembled, the free extremities of the legs 11 and 12 are pushed downwardly into the ground adjacent the plant to be protected and at such distance from the latter as to cause the lower open 100 side of the cover or shield to be adjacent the plant to be protected, or, in other words,

the basket is inverted and the closed bottom is uppermost and the open top downwardly disposed adjacent the plant. In the type of baskets which are preferably used 5 as the cover or shield there are ventilating openings at the corners, as at 16, and if desired, the lower open side of the cover or shield may be brought down close to the ground surface and the plant will be suitably ventilated. In view of the insertion of 10 the free extremities of the legs 11 and 12 in the ground and the engagement of the prop loop 10 with the surface of the ground, the improved protector will be held against overturning by the action of the wind and always retain its protective position.

It will be readily understood that the assembled support and cover or shield may be easily applied over the plant, and after it 20 has served its purpose or after the plant has gained sufficient growth to resist the damaging effect of the cold and heat, the improved protector may be removed for further service. In applying the improved protector to 25 rows of plants, the application may be expeditiously carried on in view of the simple operation involved in applying the same to the plants.

It will be understood that the proportions 30 and general dimensions of the several parts of the support and cover or shield may be modified to adapt the same to various applications or plants varying in size.

What is claimed as new is:

35 1. A plant protector of the class specified, comprising a support having a pair of divergent legs on one side with upper slotted portions formed therefrom and intermediate thereof, the free extremities of the legs 40 being adapted to be forced into the ground, the opposite side of the support having a single leg with a prop device at the lower terminal thereof to rest upon the surface of the ground, and a cover device separably 45 connected to the support and having a closed top and open bottom, one side of the cover device being removably fitted in the slotted portions.

50 2. A plant protector of the class specified, comprising a support having divergent legs at one side to partially enter the ground and

upper slotted portions on said divergent legs and a single leg on the other side of the support having a loop to terminally rest upon the surface of the ground, and a cover device separably held within the support and provided with an open bottom, the support extending over the opposite top portions of the cover device. 55

3. A plant protector of the class specified, 60 consisting of a support having two ground-penetrating legs at one side and each leg provided with upwardly opening slotted means and a single leg at the opposite side with a terminal ground-surface-engaging 65 device, and a cover with a fully open bottom separably applied at one side to the slotted means.

4. A plant protector of the class specified, 70 consisting of an arched support having a cover device held within the support, the arched support having a pair of legs with slotted means to engage a portion of the cover device, said slotted means being intermediate of the ends of the legs, and also 75 with an opposite leg with a prop device to hold the cover and support in stable position over a plant.

5. A plant protector of the class specified, 80 comprising a support having a pair of divergent earth piercing legs at one extremity and the opposite extremity formed with a closed loop, the divergent legs each being bent intermediately upon itself to form an upper slotted portion with the opening leading 85 thereto at the upper terminal thereof, and a cover device having one side removably inserted in and held by the said slotted portions.

6. A plant protector made from a single 90 piece of wire, said wire being bent upon itself to form a terminal loop and two diverging earth-piercing members, each of said members intermediate of the end thereof being provided with a substantially flattened S-shaped double loop formed therefrom and open toward the terminal loop, said loops being aligned to receive the edge of a shade at two points. 95

In testimony whereof I have hereunto set 100 my hand.

JOHN TAYLOR BOYD.
